POWDER CONTAINER

Frank H. Maloney, Elmhurst, Long Island, N. Y.,
assignor to Brass Goods Manufacturing Co.,
Brooklyn, N. Y., a corporation of New York

Application April 29, 1938, Serial No. 204,969

5 Claims. (Cl. 221—62)

This invention relates to powder containers, and particularly to heads therefor.

It is an object of the invention to provide a dispensing head which can be made of few and simple parts and at small expense for labor and material, and which will be efficient and reliable in use.

A more specific object of the invention is to provide a dispensing head consisting only of two parts, namely, the head proper, and a closure slide associated therewith, the parts being so constructed and arranged that they may be assembled with one another after both have been fully formed, and the dispensing head proper may then be applied to the top of the powder container with the parts in assembled relation.

It is a feature of the invention that the uniting of the dispensing head proper with the container serves permanently to retain the closure slide against removal.

It is a further feature of the invention that movement of the slide in one direction is limited by a stop formation of the dispensing head member, and movement in the other direction is limited by engagement with the top of the container itself.

Other objects and advantages will hereinafter appear.

In the drawing forming part of this specification, and illustrating a practical and advantageous dispensing container embodying the invention:

Fig. 1 is a plan view of a dispensing container showing the closure slide in closed position;

Fig. 2 is a view similar to Fig. 1 showing the closure slide in open position;

Fig. 3 is a fragmentary view in side elevation of the upper part of the container showing the closure slide in closed position;

Fig. 4 is a sectional view taken on the line 4—4 of Fig. 1 looking in the direction of the arrows, the view being upon a larger scale than Fig. 1;

Fig. 5 is a fragmentary, sectional view taken on the line 5—5 of Fig. 3 looking in the direction of the arrows, the view being upon the same scale as Fig. 4; and

Fig. 6 is a fragmentary, sectional view taken on the line 6—6 of Fig. 2 looking in the direction of the arrows, the view being upon the same scale as Fig. 4.

The container as illustrated comprises a can body 1. This desirably consists of a bottom piece (not shown) a side wall member 2 of sheet metal which, as illustrated, is ovate in form, 55

and a flanged cap or top member 3 which is snugly and permanently fitted to a slightly inset flange 4 at the upper end of the member 2. The top member 3 is formed with a central circular opening 5 in which a dispensing head member 6 is affixed as will be described a little farther on.

The dispensing head member slidably supports a closure plate 7 which is movable between the closed position illustrated in Figs. 1, 3 and 4, and the open position illustrated in Figs. 2 and 6. The head member 6 is a hollow dome-like member formed of sheet metal. The base portion 8 of this member is circular in cross section and is formed near its lower end with a circumferential boss or rib 9, which is pressed outward by an expanding operation to provide a circumferentially extending shoulder for engaging against the top face of the member 3.

20 Above the base portion 8 the dispensing member is formed with inwardly sloping side wall portions 10 having arcuate upper edges. The side wall portions 10 are surmounted by an arcuate boss 11 in which a dispensing opening 12 is formed. The boss 11 is formed with inturned side flanges 13 which are integral with the inturned side wall portions 10. The wall portions 10 and the flange portions 13 form reentrant angles so that the marginal portions of the boss 11 extend outward beyond the bases of the flanges 13 to form overhanging guide shoulders for guiding and retaining the closure slide 7 upon the head member. The boss 11 merges at its forward and rear ends with the cylindrical base 35 portion 8 of the head member 6.

The closure plate 7 consists of an arcuate piece of sheet metal 14 having inturned side flanges 15 for embracing the overhanging shoulders of the boss 11. The plate 7 has a central boss 16 struck upward from it, the boss 16 serving as an operating finger piece. As seen in Fig. 4, the under side of the boss 16, which is hollow, does not overlap the dispensing opening 12 when the closure slide is in closed position. The rear end of the slide 7 is formed with a downturned flange 17 which coacts with a shoulder 18 formed on the boss 11 for limiting forward movement of the closure slide 7 relative to the head member 6 to the position illustrated in Fig. 4.

Before the head member 6 has been applied to the top member 3 of the container, the parts 6 and 7 can be assembled and separated at will, there being nothing to limit rearward movement of the closure slide relative to the head

member 6. When the members 6 and 7 have been fully formed and have been brought together in assembled relation, the lower end of the base 8 which is disposed below the circumferential boss 9 is passed through the opening 5 of the member 3. With the boss 9 bearing firmly against the upper face of the member 3 the lower extremity of the member 8 is displaced outward to form the outturned flange 19 for retaining the parts strongly and securely against separation. After this operation has been performed, the member 3 is permanently assembled with the member 2, these members being formed to have a firm driving fit with one another.

As will be seen from an inspection of Fig. 6, the closure plate 7 is free to be slid from the position of Fig. 4 to the position of Fig. 6, but not to be removed altogether from the head member 6. The flange 17 strikes the upper face of the member 3 in the Fig. 6 position limiting the movement of the closure slide 7. In the position of Fig. 6 the forward edge of the closure slide 7 stands clear of the dispensing opening 12 so that the powder may be discharged through the opening 12.

It will be observed that the dispensing head consists wholly of two simple sheet metal parts, and that these parts are permanently united with one another, and with the container by a simple swaging or spinning operation, there being no need for performing soldering or brazing operations. The fact that the parts are thus united by a simple mechanical operation is a point of some importance because the container parts can be painted or enameled in advance of their assembly with the other parts, without liability of the paint being burned or of the external appearance of the parts being detrimentally affected in any way.

The curvature of the plate 7 and the boss 11 are so related to the height and to the diameter of the head member 6 that the rear edge of the plate 7 stands closely adjacent to the junction of the members 3 and 6 when the plate 7 is in the open position of Figs. 2 and 6.

I have described what I believe to be the best embodiments of my invention. I do not wish, however, to be confined to the embodiments shown, but what I desire to cover by Letters Patent is set forth in the appended claims.

I claim:

1. A powder container including, in combination, a cap member, a dispensing head member secured thereto, and a closure plate, said head member including an arcuate boss formed with overhanging guide shoulders and with a stop shoulder and having a dispensing opening, and said closure plate including inturned flanges for slidably embracing said guide shoulders and a stop flange cooperative with the stop shoulder of the arcuate boss to limit forward movement of the closure plate and cooperative with the cap member to limit rearward movement of the closure plate, the closure plate being trapped against separation from the head member by the securing of the head member to the cap member.

5 2. A powder container including, in combination, a cap member, a dispensing head member secured thereto, and a closure plate, said head member including an arcuate boss formed with overhanging guide shoulders and with a stop shoulder and having a dispensing opening, and said closure plate including inturned flanges for slidably embracing said guide shoulders and a stop flange cooperative with the stop shoulder of the arcuate boss to limit forward movement of the closure plate and cooperative with the cap member to limit rearward movement of the closure plate and said closure plate being provided with an upstanding boss constituting an operating finger piece.

10 3. A powder container including, in combination, a cap member, a dispensing head member secured thereto, and a closure plate, said head member including an arcuate boss formed with overhanging guide shoulders and with a stop shoulder and having a dispensing opening, and said closure plate including inturned flanges for slidably embracing said guide shoulders and a stop flange cooperative with the stop shoulder of the arcuate boss to limit forward movement of the closure plate and cooperative with the cap member to limit rearward movement of the closure plate, said closure plate having an upstanding hollow boss constituting an operating finger piece, the boss of the closure plate and the dispensing opening being so located that they do not overlap one another in any operative position of the closure plate.

15 4. A device for dispensing powder from a container comprising, in combination, a hollow dispensing head formed of thin sheet metal and having a circular base portion for securing the dispensing head to the top of the powder container, said head member having a top portion consisting of an arcuate boss formed with inwardly directed side flanges and having a dispensing opening, said circular base portion terminating in an inwardly sloping side wall portion connected to said flanges, a closure plate for said dispensing opening and having inturned flanges for slidably embracing the side flanges of said boss and also having an upwardly projecting portion for ready engagement with the finger of the operator.

20 5. A powder container comprising in combination, a top cap member, a hollow dispensing head member formed of thin sheet metal and having a circular base portion secured to said cap member, said head member having a top portion consisting of an arcuate boss formed with inwardly directed side flanges and having a dispensing opening, said circular base portion terminating in inwardly sloping side wall portions connected to said side flanges, a closure plate for said dispensing opening and having inturned flanges for slidably embracing the side flanges of said boss and also having an upwardly projecting portion arranged for ready engagement by the finger of the operator.

FRANK H. MALONEY.
